SAMUEL M. LANGSTON, OF WENONAH, NEW JERSEY

PAPER-CORRUGATING MACHINE

Application filed May 25, 1928. Serial No. 280,521.

One of the great difficulties in corrugating paper for use as one sheet of a single or double faced corrugated board is due to the fact that the straw paper itself has very little tensile strength, and its resistance to breaking while being bent or corrugated varies through wide limits. The method of manufacture of straw paper makes it difficult if not impossible to get either high or uniform tensile strength.

In corrugating such paper it is usually pulled into the teeth of the corrugating rolls by the rotation of these rolls, and this action causes it to drag over the teeth which are coming into mesh. There is considerable tensile strain put on the paper by reason of the dragging of the paper around the ends of the teeth. This tensile strain increases rapidly with increase in the speed of the machine.

There is also a bending strain put on the paper by the teeth, and these two strains which the paper has to stand are the limiting factors determining the speed at which one can run any particular straw paper from the supply roll through the corrugator.

Due to wide variations in tensile strength and bending qualities, some paper will fracture at the bends under the hard punishment to which it is subjected in the machine, if the paper be run at not to exceed 90 feet per minute, while other papers may be run 250 feet per minute in the same machine without showing a fracture.

Often the paper which may be run the fastest has insufficient stiffness to make a real good sheet of corrugated board. In other words, paper which is soft enough to have sufficient bending qualities to stand this punishment does not have enough rigidity in the final product. The straw paper manufacturers have great difficulty in trying to meet the somewhat conflicting requirements for softness to facilitate bending without fracture, stiffness in the final product, and capability of high speed treatment in the corrugator. This leads to considerable variation in the character of the straw paper made by different manufacturers, and which must be

handled by the machines of the corrugated board manufacturers.

A further difficulty is encountered in the corrugating of any grade of paper due to the fact that the rolls of paper during shipment from the paper mill to the corrugating manufacturer, often become lopsided, and therefore out of balance. As a result, the tension required to unroll the paper varies during each revolution of the roll. Even when there be used a particularly good sheet of straw paper which would stand the strain of running at 250 feet per minute if the roll were perfectly balanced, it is necessary that the machine be slowed down to 150 feet a minute or less, with a resulting loss of output if the roll is materially out of balance.

Difficulties also arise due to the fact that the unrolling tension varies as the supply roll decreases in diameter, and thus, even with a perfectly balanced roll there must be continuous readjustment of the brake pressure in order that the tension on the paper may be kept substantially uniform.

Attempts to balance the roll to give uniform unrolling tension are not satisfactory, because the degree of unbalanced effect or of lopsidedness varies as the roll of paper reduces in diameter. Thus, if counterbalance mechanism be employed it is necessary to frequently stop the machine and rebalance the roll.

Another point that causes trouble is that in the effort to increase production, by decreasing the shut down time on corrugating machinery, the tendency has been to use larger diameter rolls of straw paper. Such large diameter rolls act as fly wheels with accumulating effect as the speed of the machine increases, and this makes an added difficulty in tensioning of the straw paper. The straw paper, of course, has to run under a slight tension in order to keep it running true into the machine, and this accumulative momentum of the roll of paper decreases the sensitiveness with which the straw paper can be tensioned, and therefore increases the tendency for it to cut.

The main object of the present invention is to provide and maintain such uniform, defi-

nite, and comparatively low tension on the paper as it goes into the corrugating rolls, and irrespective of the size or unbalanced character of the supply roll of the straw paper.

5 In my improved machine in which I accomplish this object I provide between the supply roll and the corrugating rolls a set of feed rolls which do not give any bending strain to the paper, but positively feed the paper at a definite rate, irrespective of the varying tension on the paper between these feeds rolls and the supply roll. I automatically vary the speed of said feed rolls in respect to the speed of the corrugating rolls to compensate for the variable take-up in the corrugating rolls which is dependent on the character of the paper and its physical condition, such for instance as the percentage 20 of moisture therein. Between the positive feed rolls and the corrugating rolls I interpose a movable idler roll which rests on the paper and gives a definite tension to the paper entering the corrugating rolls. I utilize the 25 movement of this idler roll which results from variable take-up in the corrugating rolls to control the speed of the feed rolls, through a suitable variable speed device.

By means of my invention I can regulate 30 the size of the loop between the feed rolls and the corrugating rolls under all operating conditions, and deliver the paper to the corrugating rolls under a definite and uniform tension. This tension may result solely from 35 the weight of the idler roll, and the effective weight of such idler roll, and therefore the tension may be adjusted for varying conditions, such for instance as the width of the paper, the softness or stiffness thereof, 40 and the bending qualities. In addition to the weight of the idler roll there may also be provided tension bars between such idler roll and the corrugating rolls, whereby the operator of the machine may vary the tension 45 so as to obtain the best results for any particular roll of paper, as I find that different widths and different lots of straw paper will require a different tension.

In the accompanying drawings I have illustrated merely one embodiment of my invention. It will of course be understood that various changes may be made in the details of construction and the relative arrangement of the parts within the scope of my invention 55 as defined in the appended claims.

In these drawings:

Fig. 1 is an end elevation of a machine embodying my invention.

Fig. 2 is an end view of the mechanism for 60 delivering the paper at uniform tension to the corrugating rolls, and

Fig. 3 is a top plan view of the parts shown in Fig. 2.

The particular mechanism illustrated for 65 corrugating the sheet of straw paper includes

a pair of corrugating rollers 10 and 11 between which the sheet of straw paper is passed to impart corrugations to it. Beneath these rollers there is provided a pan or trough 12 for the silicate of soda or other adhesive 70 which is transferred to the crowns of the corrugations by a pair of rollers 13 and 14. A second sheet of paper is fed around a smooth surfaced roller 15 and pressed on to the adhesive, covering the crowns of the corrugations so as to make a sheet of single faced corrugated paper. The details of the corrugator form no portion of the present invention. The parts of the machine illustrated 75 may be substantially identical with that shown in my prior Patent No. 1,642,782, issued September 20, 1927, and to which reference may be had for a further description of the other parts illustrated but not here described.

The paper is delivered from a supply roll A which may be mounted in any suitable form of standard or roll support, and provided with any suitable form of brake or resistance to prevent overrunning of the roll, 80 and to give some tension on the paper. I have illustrated merely conventionally a roll support 16 with an adjustable brake 17.

In carrying out my invention I provide means which will act on the paper between 85 the supply roll and the corrugator and deliver the paper to the latter under a definite and uniform tension which may be varied in accordance with the character of the paper.

This mechanism includes a pair of feed 90 rolls 20 and 21 which act to grip the paper, positively unroll it from the supply roll A, and deliver it at the desired speed, irrespective of the varying tension required to effect the unrolling action. Although both feed rolls may be driven, preferably only the lower one is, while the upper roll 20 is carried by a pair of pivoted arms 22, one or both of which has an extension with an adjustable weight 23 whereby the frictional 95 gripping of the paper may be varied at will. 100

The feed rolls 20, 21 will deliver the paper at a constant and uniform rate, but this will not give a uniform tension on the paper, due to the varying character of the paper and the varying takeup in the corrugating rolls. Therefore, as an important feature of my invention I provide driving means which will 110 vary the speed of the feed rolls in respect to the speed of the corrugating rolls, in accordance with the condition of the paper between the two sets of rolls, so as to give the desired uniform tension. The construction of this driving mechanism and particularly the speed varying part thereof, may vary widely with- 115 in the scope of my invention.

As illustrated I provide a Reeves drive which includes a pair of driving cone pulleys 120 24 adjustable toward and from each other, a pair of driven cone pulleys 25, likewise ad- 125

justable, and a connecting belt 26. The shaft 27 of the driving pulleys 24 is connected in any suitable manner to the corrugator, whereby the speed of these driving pulleys varies directly with that of the corrugator. As shown, this connection includes a sprocket wheel 28 on the shaft 27, a sprocket wheel 29 on the corrugator or the drive shaft of the latter, and a connecting chain 30. The shaft 31 of the driven pulleys 25 is connected by a sprocket wheel 32 and chain 33 to a sprocket wheel 34 on the lower feed roll 20.

By adjusting the cone pulleys 24 toward or from each other, and simultaneously adjusting the cone pulleys 25 in the opposite direction, the speed of the feed rolls may be varied in respect to the feed of the corrugating rolls.

For controlling the speed transmission ratio there is provided an idler roller 35 which rests on the paper between the feed rolls and corrugating rolls, and rises and falls with variations in the length of the loop between the two pairs of rolls. This vertical movement of the idler roll is utilized for controlling the speed transmitting ratio of the Reeves drive. The idler roll is mounted in brackets on a pair of slides 36, vertically movable on and guided by the main frame 37 and these slides have rack bars 38 meshing with pinions 39 on a transverse shaft 40 mounted in brackets 41 carried by the main frame. This arrangement of rack bars and pinions maintains the idler 30 in parallelism with the feed rolls and rotates the shaft 40 as the idler rises or falls. The shaft 40 is provided with a sprocket wheel 42 which is connected by a chain 43 to a sprocket wheel 44 on a control shaft 45 of the Reeves drive. This shaft 45 has its opposite end portions provided with threads of opposite pitch, and carries nuts 46 for swinging levers 47 pivoted intermediate of their ends and engaging the cone pulleys. By rotating the shaft 45 in one direction the drive pulleys 24 will be moved toward each other and the driven pulleys 25 moved apart to drive the feed rolls at higher speed, while upon rotating the shaft 45 in the opposite direction the cone pulleys 24 will be separated and the pulleys 25 brought together to drive the feed rolls at slower speed. Thus with the feed rolls 20, 21, delivering paper at exactly the speed required by the corrugating rolls, the loop of paper between will remain of constant length, and the idler 35 will remain with its axis in fixed position. If the corrugating rolls take in the paper at faster or slower speed, the idler will rise or fall, and thereby increase or decrease the speed of the feed rolls.

The idler roll resting upon the paper gives a definite tension on the paper, which tension remains constant, irrespective of the varying tension in the paper as it goes to the feed rolls. The effective weight of the idler, and therefore the tension of the paper, may be varied at will. The mechanism for accom-

plishing this is shown as including a drum 48 on the shaft 40, with a cord or tension member 49 secured thereto, and extending over a sheave 50 to a weight 51. This weight normally tends to rotate the shaft 40 in a counter-clockwise direction which thus tends to lift the idler 35 and relieve the paper of the weight of the idler and slides. By adjusting the weight 51 in respect to the relative sizes of the drum 48 and idler 50, and the diameter of the pinions 39, the effective weight of the idler 35 may be controlled so that there will be the desired comparatively low tension on the paper of the loop.

In addition to the foregoing means for controlling the tension, the corrugator itself may have an adjustable device for readily varying the tension if desired. I have shown somewhat diagrammatically a common form of device for accomplishing this purpose, which includes a pair of rollers 52, 53, with an intermediate roller 54 carried by pivoted arms and movable into or out of position between the rollers 52, 53. By raising or lowering the roller 54 the tension on the paper may be varied, or these parts may be adjusted to give the desired fixed tension, and the idler roll 35 may be counterbalanced so that there is very little tension on the paper on its way to the tension rollers 52, 53 and 54.

For threading up the machine I provide means for positively lifting the idler 35 and locking it in raised position. This is shown as a hand wheel 55 connected to the sheave 50, and a pawl 56 for engaging a tooth or notch on a ratchet wheel 57, also secured to the sheave. Similar or other means may also be provided for raising the feed roll 21 and locking it in raised position.

By means of my improved construction and arrangement of parts, the machine may be adjusted in accordance with the tensile strength and bending qualities of the particular paper to be corrugated, and the paper delivered to the corrugating rolls under a fixed and uniform, but comparatively low tension which is not in any way dependent upon the brake pressure, unbalanced condition, or size of the supply roll. The speed of the ordinary machine may be increased far beyond that which is possible with corrugated paper of low tensile strength or poor bending qualities. Even with the very best grades of paper a uniformity of product and a high speed of operation are possible.

The Reeves drive which is illustrated for varying the speed of the feed rolls in accordance with variations in the length of the loop between the feed rolls and the corrugating rolls, is merely one of the many mechanical devices which may be utilized for the purpose. For instance, the feed roll 20 may be driven directly or indirectly by an electric motor, and the movement of parts supporting or connected to the idler 35 may operate the

rheostat of the motor to vary the speed of the latter. If the feed roll is driven directly from the corrugator or from the same source of power, the power transmitting connections 5 might have various other forms of speed varying means of such character as permit of the comparatively slight speed variations necessary to maintain the substantially constant length of loop. As the slides have a 10 vertical movement the effective weight of the idler on the paper will remain constant whether the idler be in raised or lowered position. Commercially satisfactory results 15 may be obtained by supporting the idler on approximately horizontally extending pivoted arms.

Having thus described my invention, what I claim as new and desire to secure by Letters Patent is:

20 1. A machine for making corrugated paper, including a pair of intermeshing corrugating rolls adjustable toward and from each other, means for supporting a supply roll of paper to be corrugated, and means 25 for maintaining the tension on the paper delivered to the corrugating rolls substantially constant irrespective of varying resistance to the rotation of the supply roll and varying takeup of the paper in the corrugating 30 rolls including a feeding device for withdrawing paper from said supply roll, means for varying the speed of said feeding device in accordance with variations in the takeup of the paper in the corrugating rolls.

35 2. A machine for making corrugated paper, including a pair of corrugating rolls having intermeshing teeth for drawing the paper therebetween and imparting corrugations thereto, said rolls being adjustable to 40 vary the depth of the corrugations imparted to the paper and the rate at which the paper is drawn between said rolls, a feed roll for delivering paper, means for varying the speed of the feed roll in accordance with the varying 45 rate at which the paper is drawn between the corrugating rolls, and an idler engaging the paper between the feed roll and the corrugating rolls, said idler being supported by the paper and imparting substantially constant 50 tension to the paper as it enters the corrugating rolls.

3. A machine for making corrugating paper, including a pair of corrugating rolls 55 having intermeshing teeth for drawing the paper therebetween, bending it around said teeth and forming the corrugations, and means for maintaining substantially constant the tension on the paper delivered to said 60 corrugating rolls irrespective of varying takeup of the rolls, said means including a feed roll for delivering the paper, an idler supported against downward movement by the paper between said feed roll and said 65 corrugating rolls, and means for varying the

speed of the feed roll in accordance with the varying takeup of the corrugating rolls, said means being operated by the vertical movements of said idler roll.

4. A machine for making corrugated paper, including a pair of corrugating rolls having intermeshing teeth for drawing the paper therebetween, bending it around said teeth and forming the corrugations, a pair of feed rolls for delivering the paper without imparting bending strains thereto, and means for maintaining the tension on the paper between said feed rolls and said corrugating rolls substantially constant and irrespective of variations in the takeup of the paper in 80 said corrugating rolls.

5. A machine for making corrugated paper, including a pair of corrugating rolls, a frame having a feed roll at the upper part thereof, a pair of vertically movable rack bars on the side of said frame toward said corrugating rolls, an idler carried by said rack bars, a transverse shaft below said idler and mounted in said frame, pinions on said shaft engaging said rack bars, a drum on 90 said shaft, a weight having a cable wound on said drum and tending to rotate said shaft in a direction to lift said rack bars and said idler roll, and partially counterbalancing the weight of the latter and the rack bars, driving means for said feed roll, and means controlled by the oscillations of said shaft for varying the speed of said feed roll.

6. A machine for feeding paper to a pair of corrugating rolls having intermeshing teeth for drawing the paper therebetween, bending it around said teeth, and forming the corrugations, including a feed roll for delivering the paper, an idler roll for engaging the loop of paper between the feed roll and the corrugating rolls, movable supports for said idler roll and permitting the up and down movement of the latter in accordance with the length of the paper loop between the feed roll and the corrugating rolls, a gear wheel rotated by said supports, a Reeves drive for driving said feed roll, and means driven by said gear wheel for varying the driving speed ratio of said Reeves drive upon upward or downward movement of said idler.

7. A machine for feeding paper to a pair of corrugating rolls having intermeshing teeth for drawing the paper therebetween, bending it around said teeth, and forming the corrugations, including a feed roll for delivering the paper, a pair of movable supports, an idler carried thereby and resting upon the paper between the feed roll and the corrugating rolls, a gear driven by one of said supports, a Reeves drive including a drive shaft, a driven shaft and a control shaft, driving connections between said drive shaft and said corrugating rolls, driving connections between said driven shaft and said feed roll,

and operating connections between said gear and said control shaft.

8. A machine for feeding straw paper from a supply roll to corrugating rolls, including a feed roll, an idler engaging the paper between said feed roll and the corrugating rolls, a Reeves drive having driving and driven pulleys, a means for driving said drive pulley in fixed speed relationship to said corrugating rolls, means for driving said feed roll from said driven pulley, a control shaft for said Reeves drive, movable supports for said idler, and operating means connected to said supports and operatively connected to said control shaft.

9. A machine for feeding straw paper from a supply roll to corrugating rolls, including a feed roll, an idler engaging the paper between said feed roll and the corrugating rolls, a Reeves drive having driving, driven and control shafts, means for driving said drive shaft in fixed speed relationship to said corrugating rolls, means for driving said feed roll from said driven shaft, a reciprocatory member connected to said idler to permit the movement of the latter in a substantially vertical direction and mechanically operating connections for positively and directly oscillating said control shaft upon vertical movement of said idler.

10. A machine for feeding straw paper to a pair of intermeshing corrugating rolls, means for supporting a supply roll of paper to be corrugated, a feed roll for withdrawing paper from said supply roll and delivering it to said corrugating rolls, an idler resting on the paper between the feed roll and the corrugating rolls, a pair of vertically movable members for supporting said idler, means for engaging said members to positively lift the idler, and counterbalancing weights connected to said members and also tending to lift said idler.

Signed at Camden, in the county of Camden and State of New Jersey, this 23rd day of May, A. D. 1928.

SAMUEL M. LANGSTON.
